REINFORCING FABRIC FOR VEHICLE TIRES.

1,407,012.

Specification of Letters Patent. Patented Feb. 21, 1922.

Application filed December 24, 1920. Serial No. 433,062.

To all whom it may concern:

Be it known that I, THOMAS BRANSON, a citizen of the United States, residing in Philadelphia, in the county of Philadelphia and State of Pennsylvania, have invented certain new and useful Improvements in Reinforcing Fabrics for Vehicle Tires, whereof the following is a specification, reference being had to the accompanying drawing.

10 The invention relates to reinforcing fabrics more particularly useful in the manufacture of vehicle tires of the type ordinarily known as cord tires.

In tires of this kind, the reinforcing fabric layers, usually coated or embedded in rubber, are so arranged in the tire structure as to be capable of resisting strains induced only in one direction. Accordingly, the paramount requisite of a fabric best suited to 20 this purpose, is that it possess great tensile strength. Hence, the main strands or warps of such fabrics are usually in the form of stout cords, which, as can be readily inferred, are arranged to extend longitudinally 25 of the fabric structure.

The object of my invention is to dispose the main strands or cords of the reinforcing fabric in such manner that they will be free, not only to admit of being closely compacted laterally, but also to be stretched absolutely taut when placed under tension without incurring any interference whatever from the binder threads of the ground work by which they are incorporated into the 30 fabric structure. This end I attain by simply inlaying the cords in a ground work of comparatively fine gauge, binder threads having just sufficient strength to preserve the integrity of the fabric, so that the latter 35 will not yield to undue distortion in the course of being coated with, or embedded in the rubber as above noted.

Other objects and advantages of my invention will become apparent from the detailed description which follows.

The drawing represents, more or less diagrammatically, a fragment of a fabric structure conveniently embodying my invention.

From this illustration, it will be observed 50 that the main strands or cords indicated by the numerals 1 to 9 inclusive, extend longitudinally of a fabric structure and are inlaid in a ground work of interconnected binder threads of a comparatively lighter or

finer gauge, said binder threads being represented by characters 10 to 13 inclusive. These binder threads are interknit to form a series of loop chains 15 to 19 inclusive, which chains are coextensive with the longitudinally running cords and appear upon, 60 what I will designate for convenience, the face of the fabric.

The loop chains are tied together by a peculiar preordering of the intertwining of the binder threads in the course of knitting 65 operation, the result of which may be briefly described as follows:

Tracing, for example, the course of the binder thread 10, it will be noted that the latter is formed into a loop 20 (only partly 70 shown) in the first chain 15 of the series, this loop being held by a superjacent loop 21 in the same chain. After passing through the loop 21, the thread 10 extends, in an angular direction, to the back of the fabric 75 structure, incidentally embracing, from behind, the cords 3, 4, 5, and 6, and thereafter again makes its appearance, at the front of the fabric, in the form of a loop 22 in the comparatively remote chain 18. This loop, 80 it will be noted, extends askew of the cords 7 and 8 in order to bind them, and is held by the superjacent loop 23 of chain 18, the last mentioned loop being likewise disposed askew of the cords 7 and 8, but slanted in a 85 direction opposite to that of loop 22. After passing through the loop 23, the thread 10 again recedes to the back of the fabric and embraces the cords, 3, 4, 5 and 6 a second time, and in so doing extends at an inclination counter to that of its first deviation, 90 finally reappearing as another loop 24 in the chain 15. The latter loop is connected to the loop 20 by the loop 21, previously referred to, while said loop 24 is held by a 95 superjacent companion loop 26 of the chain 15. Tracing the course of the thread 10 still further, it will be observed to repeat its deviation to the right behind the cords, 2, 3, 4 and 5, and forms a second loop 27 in 100 the chain 18 which loop is in turn tied to the loop 22 by the intervening loop 23 of another binder thread. From this point on, the thread 10 returns again, after a manner already understood, to form another loop 105 (not shown) in the chain 15. By virtue of such continual zigzagging of the binder thread in order to be formed into alternate

loops of remotely spaced chains, the cords 3, 4, 5 and 6 are effectively tied into the fabric structure. By similar reasoning, it will become manifest that the binder thread 5 11, in zigzagging between chains 16 and 19, serves to incorporate the cords 5, 6, 7 and 8 in a like manner. Furthermore, it is to be particularly noted that the fields of the zigzagging of the several binder threads overlap so that one group of cords, embraced at 10 the rear of the fabric, is bound unto the next, while the loops of the chains skewed alternately in different directions serve to tie together adjacent pairs of the cords at 15 the front of the fabric.

A fabric structure having the characteristics herein set forth, while being sufficiently flexible laterally to permit the flow of the rubber in the interstices between the longitudinal running cords during manufacture 20 into a composite tire material, will not yield to undue distortion in being passed between the pressure rolls of the machine in which this operation is performed. In practice, 25 I employ binder threads of very light gauge having the proper tensile strength to preserve integrity of the fabric in the course of the process above referred to, but which notwithstanding occupy but a comparatively 30 small space intermediate the cords. As a consequence, the cords may assume positions in very close proximity to one another when the fabric is placed under tension longitudinally, and by reason of being only inlaid in 35 the structure, the cords are rendered free to become taut under tension without interference from the ground work by which they are tied.

The fabric structure of my invention may, 40 as will be readily understood by those skilled in the art of knitting, be readily produced on any ordinary knitting loom by predetermining the shifting of the guides both for the cords and binder threads with respect 45 to the knitting needles.

Having thus described my invention, I claim:

1. A textile structure of the character described including in combination, a series of cords extending longitudinally of the fabric, and a ground work in which said cords are inlaid, said ground work comprising a series of comparatively light binder threads interknit to form, in alternation with the cords, a series of coextensive loop chains appearing on the face of the fabric structure, the binder threads, in order to form loops in remote loop chains, being zigzagged crosswise at the back of the fabric to embrace the group of cords in the interval, and the fields comprehended by the zigzagging of the several binder threads, arranged to overlap, so that one group of the cords is bound unto the next. 50 55 60

2. A textile structure of the character described including in combination, a series of cords extending longitudinally of the fabric, and a ground work in which said cords are inlaid, said ground work comprising a series of comparatively light binder 65 threads interknit to form a series of longitudinally running loop chains, the loops of said chains lying askew in alternatively opposite directions across a number of said cords at the face of the fabric, and the binder 70 threads, in order to form alternate loops in remote loop chains being zigzagged crosswise at the back of the fabric to embrace the group of cords in the interval, and the fields comprehended by the zigzagging of the several binder threads, arranged to overlap so that one group of cords is bound unto the next. 75 80

In testimony whereof, I have hereunto signed my name at Philadelphia, Pennsylvania, this 16th day of December, 1920.

THOMAS BRANSON.
